FUSE CARRIER

Albert B. Rypinski, Laurelton, N. Y., assignor to
Metropolitan Device Corporation, a corporation
of New York

Application January 7, 1936, Serial No. 57,918

3 Claims. (Cl. 200—133)

The invention herein disclosed relates to a fuse carrier or holder of the pull-out type.

Such fuse carriers are frequently used for barrel type fuses and normally consist of a base or support of stiff electrical-insulating material, fuse clips and switch blades secured to one side of the base and positioned to receive and hold fuses, and a handle pivotally secured to the other side of the base. Commonly, such fuse carriers 10 are adapted to carry at least two fuses. The switch blades, in the operative position of the carrier are received in switch clips which support the carrier. The carrier may be removed from the operative position by pulling on the 15 handle secured to the carrier.

The barrel type fuses, such as are usually held by such fuse carriers, generate a considerable amount of heat under normal full load. In the fuse carriers heretofore employed this heat generated by the fuses is readily transmitted through the base or support to the handle that is grasped by the hand to remove the fuse carrier. With fuses of large capacity, the heat transmitted to the handle of the fuse carrier is sufficient to heat 20 the handle so that it is uncomfortably hot to touch and prevents ready withdrawal of the fuse carrier; and it is an object of this invention to produce a fuse carrier in which this condition does not prevail.

30 A fuse carrier constructed in accordance with this invention is provided with an air space between the support for the fuse clips and the handle provided for inserting and removing the fuse carrier. There is, therefore, no direct transfer of heat by conduction from the fuse-clip support to the handle and the circulation of air set up in the air space carries the heat away from the support by convection. The fuse carrier thus constructed includes a fuse clip support consisting 35 of a sheet of stiff, fibrous, electrical-insulating material to one side of which the fuse clips are secured. To the other side of the fuse-clip support there is secured in spaced relation thereto another sheet of stiff material and to this latter sheet of material the handle is secured. The space between the two pieces of sheet material constitutes an air space through which air circulates.

40 A fuse carrier constructed in accordance with this invention is illustrated in the accompanying drawing in which:

Fig. 1 is a front elevation of the fuse carrier; Fig. 2 is a sectional elevation taken along the line 2—2 of Figure 1; and

45 Fig. 3 is a rear elevation thereof.

The fuse carrier illustrated in the drawing includes a fuse-clip support 1 made from a sheet of stiff, fibrous, electrical-insulating material. To one side of the fuse-clip support, there are secured four combined fuse clips and switch 5 blades 2, arranged in pairs and positioned so that each pair is adapted to receive and hold a fuse as illustrated. Each of these combined fuse clips and switch blades includes a base 2a secured to the support 1 by rivets, laterally extending 10 spaced semi-cylindrical elements 2b extending from opposite sides of the base and adapted to receive a barrel type fuse therebetween, and a switch blade 2c formed as a lateral extension of 15 the fuse-clip base.

To the side of the support 1, opposite to that to which the fuse clips are secured, there is secured to the support by four rivets 3 a sheet of stiff, fibrous, electrical and heat insulating material 4 of the same dimensions as the support 1. The sheet material 4 is spaced from the support 1 by spacers 5 surrounding the rivets 3 and between the support and the sheet material 4. There is thus formed between the support 1 and the sheet material 4 an air space through which 20 air may circulate.

25 By the rivets 3, there is secured to the sheet material 4, the metal base 6 of a handle 7. The handle 7 is shaped as shown and it is pivotally secured to the handle base 6 by a plate 8 spot welded to the handle base 6. The plate 8 has semi-cylindrical extensions 8a formed therein 30 that receive the ends of the handle 7.

35 From the above description of the fuse carrier illustrated in the drawing it will be apparent that the transfer, by conduction, of heat generated by the fuses in the fuse clips to the handle 7 is cut off by the air space between the support 1 and the handle. Furthermore, the circulation of air through the air space set up by the heat generated by the fuses transfers, by convection, 40 the heat to the circumambient atmosphere.

45 It will be obvious that various changes may be made by those skilled in the art in the details of the embodiment of the invention illustrated in the drawing and described above within the principle and scope of the invention as defined in the appended claims.

I claim:

50 1. A fuse carrier of the pull-out type comprising a fuse clip support consisting of a sheet of stiff electrical insulating material, spaced fuse clips and switch blades mounted on one side of the support and positioned and adapted to receive and hold a fuse, another sheet of stiff in- 55

sulating material, a metal plate, a handle pivotally secured to the plate, spaced securing means for securing the metal plate and the two sheets of electrical insulating material together and small spacing elements between the sheets of insulating material whereby an unobstructed passage is provided between the sheets of insulating material for the free passage of air therebetween.

2. A fuse carrier of the pull-out type comprising a fuse clip support consisting of a sheet of stiff electrical insulating material, spaced fuse clips and switch blades mounted on one side of the support and positioned and adapted to receive and hold a fuse, another sheet of stiff insulating material of the same size as said fuse clip support, a metal plate, a handle pivotally secured to the plate, spaced securing means for securing the metal plate and the two sheets of electrical insulating material together and small spacing elements between the sheets of insulating material and surrounding said securing means whereby an unobstructed passage is pro-

vided between the sheets of insulating material for the free passage of air therebetween.

3. A fuse carrier of the pull-out type comprising a fuse clip support consisting of a sheet of stiff, fibrous electrical insulating material, spaced fuse clips and switch blades mounted on one side of the support and positioned and adapted to receive a fuse, a handle support consisting of a sheet of stiff electrical insulating material, a handle mounted on one side of the handle support including a metal plate and a handle pivotally secured to the plate, rivets extending through and securing together the fuse clip support, the handle support and the metal plate, the fuse clip support having openings therethrough for the passage of air, and small spacing collars surrounding the rivets between the fuse clip support and the handle support, whereby an unobstructed passage is provided for the circulation of air through the fuse clip support and between the fuse clip support and the handle support.

ALBERT B. RYPINSKI.
